RIVET SETTING MACHINE

Louis C. Huck, Grosse Pointe Village, and Ralph A. Miller, Detroit, Mich., assignors, by direct and mesne assignments, to Huxon Holding Corporation, Detroit, Mich., a corporation of Michigan

Application May 2, 1932, Serial No. 608,682
Renewed June 15, 1936

27 Claims. (Cl. 218—19)

The invention relates to rivet setting machines or machines for applying rivets to structural elements for securing them together.

Particularly, the invention constitutes an improvement over that embodied in our co-pending application for patent, Serial No. 560,289, filed August 31, 1931, which relates to a machine of the general type designated above. Such machines are adapted to set rivets of the general type shown and described in the co-pending application for patent, for example, of Louis C. Huck, Serial No. 545,004, filed June 17, 1931. The rivet may comprise a female member having a tubular body portion and preferably a rivet head at one end thereof, which cooperates with a male member extending longitudinally therethrough and which has a head at one end engaging the opposite end of the female member. The rivet as thus assembled is inserted through openings in a plurality of structural elements to be connected thereby until the head on the female member engages the side of the structure adjacent thereto. The shank of the male member projects outwardly from the rivet head of the female member and by pulling it through the female member in the direction outwardly from the head of the latter, and applying the reactionary force of such operation to the latter head, the body portion of the female member may be formed with a head at the opposite side of the structure.

The principal objects of the present invention are to provide improvements in a machine for applying rivets of the aforesaid character, which is capable of a more universal use, particularly for setting rivets in less accessible locations such as in corners, recesses and the like; to provide a machine of improved nature which is constructed of parts so related and adjustable, that an operator of the machine may control the rivet setting operation more satisfactorily, particularly in structural openings where it would otherwise be difficult to operate a rivet setting machine; to provide an improved rivet setting machine for applying rivets of the above mentioned character which is particularly adapted to grip and pull the male member through the female member and thereby form a head at one end of the latter, and then to continue the pull on the male member until the tension thereon breaks such male member approximately at the point it emerges from the female member at that side of the structure being riveted, adjacent the machine; to provide an improved machine for accomplishing the last mentioned result which so operates that the broken male member is moved on through the gripping

means upon insertion of the next rivet, and in this manner automatically removed; to provide an improved machine for setting rivets in which the male member is finally broken, in which moving parts are efficiently cushioned against the recoil after the male member is broken; to provide an improved machine for applying rivets of the aforesaid character which is readily adaptable for the application of rivets of different sizes and dimensions; to provide a machine of light construction which may be manually manipulated easily, to thereby facilitate the application of rivets and in general to permit an operator to set rivets rapidly; to provide a machine for setting rivets which is so constructed that powerful rivet setting forces may be applied, without requiring a bulky, heavy and unwieldy mechanism and one that would interfere with the use thereof in various structural locations; and in general to provide a rivet setting machine for applying rivets of the aforesaid character, which is extremely efficient in operation, simple in construction, light in weight, more universal in application, and which may be manufactured inexpensively.

Other objects of the invention will be apparent from the following description, the drawings relating thereto, and the claims hereinafter set forth.

For a better understanding of the invention reference may be had to the accompanying drawings, forming a part of the specification, wherein:

Figure 1 is a longitudinal cross-sectional view of a rivet setting machine constructed according to one form of the invention;

Fig. 2 is a plan view of the machine shown by Fig. 1, with certain parts shown in cross section for the purpose of illustrating certain details more clearly;

Fig. 3 is a cross-sectional view on a larger scale, taken substantially along the line 3—3 of Fig. 1, and illustrating certain details of the connection between the piston rod and an operating arm;

Fig. 4 is a cross-sectional view on a larger scale, taken substantially along line 4—4 of Fig. 1, illustrating details of a fluid controlling valve employed in the machine;

Fig. 5 is a right end view of the machine as shown by Figs. 1 and 2;

Fig. 6 is a fragmentary and longitudinal cross-sectional view on a larger scale, illustrating more particularly the rivet setting jaws and parts for manipulating them;

Fig. 7 is a cross-sectional view on a larger scale, taken substantially along the line 7—7 of Fig. 6;

Fig. 8 is a cross-sectional view on a larger scale, taken substantially along the line 8—8 of Fig. 6;

Fig. 9 is a cross-sectional view on a larger scale, taken substantially along the line 9—9 of Fig. 6;

5 Fig. 10 is a cross-sectional view on a larger scale taken substantially along line 10—10 of Fig. 6;

10 Fig. 11 illustrates in cross section the manner in which a rivet of the general type described is first applied to the structural elements prior to employing the rivet setting machine, and

15 Fig. 12 illustrates an extension riveting anvil which may be used if a rivet is to be set in a relatively deep, narrow opening.

Fig. 13 is a cross-sectional view illustrating a 15 spiral or an annular thread and groove arrangement that may be used on the jaws and male rivet member.

Referring to Figs. 1 and 2, spaced cylinder heads 10 and 11 are provided which support between them a cylinder wall 12 having outwardly directed peripheral flanges 13 and 14 at opposite ends, seated in annular recesses 15 and 16 in the heads respectively. Such heads and the wall 12 are secured together by bolts 17 passing through 20 marginal portions of the heads, and longitudinally over the outer surface of the cylinder wall. Within the cylinder, a piston 18 is provided which has its central portion apertured to receive a piston rod 19, and this rod has a shoulder 20 at one 25 side of the piston for holding the latter in place, and at the opposite side of the piston, a lock nut 21 threaded thereon to hold the piston against the shoulder. For holding the lock nut in position against loosening, a wire or the like 22 may 30 extend partially around the periphery of the nut in a groove therein, and then project radially through an opening in the nut and partially into an opening (not shown) in the rod. At the left side of the piston, as seen in Fig. 1, a pin 23 is 35 provided which is threaded into the end of the rod as shown at 24, and this pin is reciprocatory in a bearing sleeve 25 disposed in an opening centrally formed in the cylinder head 10. The opposite end of the piston rod slidably projects 40 through an opening in the cylinder head 11 and this opening extends entirely through the head, in contrast to the opening in the head 10 having the sleeve 25. A stuffing box 30 is threaded into the head 11 around the rod 19 to prevent the 45 escape of fluid under pressure in the cylinder along the piston rod to the outer side of the head. The slidable mounting of the piston rod in the heads 10 and 11 assists in locating and guiding the movement of the piston, and both 50 supports are desirable particularly when the piston is provided with cup washers 26 and 27 bolted to the outer margin of the piston as indicated at 27', as wear on such washers is reduced to a 55 minimum.

60 The head 10 also serves as a support for a handle 31 which is secured thereto at its upper end by means of bolts 32 as shown by Fig. 2, and at its opposite end to one end of a casting 33 by means of bolts 34. This casting at its opposite 65 end is secured by bolts 35 to the lower side of the cylinder head 10. It will be noted that the handle member 31 is provided with hand and finger abutments 37 and 38 and in general is shaped to facilitate manual gripping of the machine.

70 For supplying fluid under pressure to the cylinder, to reciprocate the piston therein, the handle 31 and the casting 33 are of hollow construction and a fluid pressure supply line 40 is connected to the casting 33 to supply fluid under 75 pressure to both the handle and casting. The

space in the casting 33 communicates with the space interiorly of the handle 31 by means of a recess 41, so that fluid under pressure will enter the handle, and the opposite end of the casting is open at its point of connection with the cylinder head 10. The valve arrangement for controlling the flow of the fluid is located on the outer side of the cylinder head 10 as shown by Figs. 1 and 4, and as shown best by Fig. 4, such arrangement includes passageways 44, 45, 46 and 47, the passageways 44 and 45 being located in the upper half of the cylinder head, and passageways 46 and 47 in the lower half. In each passageway a valve stem 48 is mounted for vertical reciprocatory movement, and slidably projects 15 through an opening 49 into a space 50 located centrally of the cylinder head and open to the atmosphere. The valve stem also projects slidably through a valve seat 51 secured in the passageway, and on the other side of the valve seat, the 20 stem slidably passes through a valve disc 52 having a sharp marginal edge 53 on its face adjacent the seat adapted to engage a sealing ring 54 located in a groove in the seat. For lifting the valve disc 52, it being slidably mounted on the valve 25 stem, the latter is provided with a shoulder 54', and on the other side of the disc the stem is provided with a second valve disc 55 rigidly mounted thereon as by threading. The latter disc similarly to the disc 52, has a marginal sharp edge 30 56 on its face for engaging a sealing ring 57 located in a groove in the upper face of the disc 52. The disc 52 has one or more openings 57' along the valve stem so that fluid under pressure 35 in the space in the passageway at the disc side of the seat may meter through the disc along the stem when the disc 55 is raised thereabove. When the disc 52 is raised, the fluid may also flow through larger openings 59 in the seat 51 into the passageway below the seat. Normally the stem 40 is urged into the valve closing position by means of a helical spring 60 encircling the stem and engaging at one end the valve seat 51 and at its other end a collar 61 rigidly mounted on the stem.

When the stem 48 is in a valve closed position, 45 it is apparent that the stem will be held downwardly by means of the spring 60, and that the discs 52 and 55 will entirely close the valve. When the stem is moved into the valve lifting position, the disc 55 will initially be raised, and this will 50 permit a small flow of fluid under pressure through the disc 52, and openings 57', then through seat 51, and this is desirable because the pressure of the fluid on both sides of the valve 55 may then be somewhat neutralized, and this result may be obtained more easily by lifting the small valve disc 55 instead of the larger valve disc 52. After the pressure is somewhat neutralized, it is not difficult to raise the disc 52 to allow 60 the fluid to flow more rapidly through the valve seat. For the purpose of illustrating the function of the four valves involved, the valve in passageway 44 is indicated at 65, that in passageway 45 at 66, that in passageway 46 at 67 and that in passageway 47 at 68.

Still referring to Fig. 4, the casting 33 has an offset passageway 70 communicating directly with the passageway 46 in the valve arrangement at the valve disc side of the valve seat, and since 70 the casting is in direct communication with the fluid pressure supply line 40, the passageway 46 will always have fluid under pressure therein at this side of the valve. As shown best by Figs. 1 and 2, the passageway within the handle 31 com- 75

municates with a smaller passageway 71 in the handle casting and the latter in turn communicates with a passageway 72 extending into the upper part of the cylinder head 10, and then communicating with the passageway 45 in the valve arrangement, above the seat therein. Therefore, it will be apparent that the vertically aligned passageways 45 and 46 above and below the valve seats therein respectively are in direct communication with the fluid pressure line 40. Referring now to Figs. 2 and 4, the passageway 45 below the valve seat 51 communicates with a laterally extending aperture 74, and the latter in turn communicates with an upwardly extending passageway 75 in the cylinder head at one side of the passageway 45, and such passageway 75 at its upper extremity communicates with a passageway 76 formed in a casting 11 secured by bolts 78 and 79 at opposite ends to the cylinder heads 10 and 11 respectively. This casting has a longitudinally extending rib type passageway 80 extending to the cylinder head 11, and such passageway then communicates with a passageway 81 extending downwardly through the head 11 and then laterally through the head as indicated at 82 in Fig. 1, where it communicates with the interior of the cylinder at the right side of the piston. Accordingly, when valve 66 is open, fluid under pressure will flow into the right end of the cylinder. As seen in Figs. 1 and 4, the passageway 46 communicates with an opening 83 extending directly through the cylinder head 10 and communicating with the interior of the cylinder at the left side of the piston, such opening 83 being at the spring side of the valve seat in the passageway. Accordingly, when valve 67 is open fluid under pressure will flow to the left side of the cylinder. As shown by Fig. 4, the passageway 44 above the valve seat communicates with an opening 85 extending laterally through the cylinder head 10 and communicating directly with the interior of the cylinder, whereas below the valve seat, the passageway communicates with a laterally extending opening 86 in turn communicating with an exhaust passageway 87 extending downwardly through the cylinder head and finally opening to the atmosphere through an opening in the casting 33. The passageway 47 at the spring side of the valve seat communicates with a laterally extending passageway 88 also in communication with exhaust passageway 87 whereas on the other side of the valve seat the passageway communicates with an opening 89 in turn communicating with a passageway 90 extending upwardly and to a longitudinally extending passageway 91 extending parallel to the passageway 88 in the casting 11. Such passageway 91 also communicates with the right end of the cylinder through a downwardly extending passageway 92 through the head 11, as seen in Fig. 1.

For operating the valve, a trigger 93 is provided, as seen in Fig. 1, which is pivoted as indicated at 94 to lugs 95 on the handle 31, and such trigger is normally maintained in its lowermost position by means of a spring pressed pin 96 having a spring 97 therein engaging the base of a recess in the handle casting, in which the pin is slidably mounted. Such trigger adjacent the handle has a bar 98 fastened in a slot therein which extends into the passageway 50 shown by Fig. 4, and between the ends of the valve stems projecting into such passageway as shown in broken lines. Since the trigger 93 normally will be maintained in its lowermost position, the valves

65 and 66 normally will be open, and the valves 67 and 68 will normally be maintained in their closed positions.

Now when the trigger 93 is pulled slightly, it is apparent that the first thing that will happen is that the smaller valve disc 55 on valves 67 and 68, will initially open to allow neutralization of pressure on both sides of the valve, and this in turn will facilitate opening the valve discs 52 on such valves, to fully open the valves in the manner desired. As valves 67 and 68 open, it is of course apparent that valves 65 and 66 will close and that when one set of valves is fully open, the other set will be fully closed. When valves 65 and 66 are closed, the left side of the cylinder is closed to the exhaust passageway 87 through valve 65, and fluid under pressure to the right end of the cylinder is shut off, since the closing of valve 66 cuts off communication between the passageway in the handle 31 to the passageway 75. As valve 67 opens, fluid under pressure flows through the casting 33 through the passageway 46, through the valve therein, through the passageway 83 and into the left side of the cylinder, while the opening of valve 68 permits the right end of the cylinder to exhaust through the passageways 92, 91, 90, 89, the valve 68, and into the exhaust passageway 87. The piston then will move to the right. Upon release of the trigger 93, the valves 67 and 68 will close, and valves 65 and 66 will open. It then will be apparent that fluid under pressure will communicate with the right end of the cylinder, and fluid will be allowed to exhaust from the left end of the cylinder into the exhaust passageway 87, thus moving the piston to the left.

It will be noted in Fig. 1 that one of the bolts 27' at the margin of the piston has an extension, indicated at 94', which is substantially aligned with the exhaust opening 92 in head 11. This pin is adapted to move into the opening 92 when the piston approaches head 11, and serves as a metering element to reduce the effective size of the exhaust passageway gradually and hence to prevent rapid exhaust of fluid at the right side 45 of the cylinder when the piston is moving near to and toward such head. In this way a fluid cushion is provided to cushion the piston, and the primary purpose thereof will be presently described.

For the purposes of setting rivets with the apparatus described, that end of the piston rod 19 projecting beyond the cylinder head 11, has as best shown by Fig. 3, a slot indicated at 100 and at opposite ends of this slot, bearing elements 101 and 102. Each of such elements preferably has ribs 103 at opposite sides of the slot to retain the elements in position. It will be appreciated that either element may be inserted by placing it longitudinally in the slot, with the ribs 103 above and below the slot, and then turning the element until the ribs are disposed transversely of the slot, when the elements may be moved into the end positions. The recess thus provided in the end of the piston rod receives one end of an arm 104 pivoted as indicated at 105 to offset bracket members 106 integral with the cylinder head 11. That part of the arm in the slot in the end of the piston rod, preferably has rounded sides as indicated at 107 to facilitate movement of the arm about its pivot upon reciprocatory movement of the piston and piston rod.

The opposite end of the arm 104 projects upwardly through an aperture 108 into a cylindrical barrel 109 which is secured as indicated at 110

to the upper side of the cylinder head 11. It is to be noted that the length of the arm portion above the pivot 105 is much less than the length of the arm portion below the pivot, and consequently a greater force may be exerted by the upper end of the arm, with a smaller force acting on the lower end of the arm, because of the mechanical leverage obtained. Around the arm and the end of the piston rod projecting from the cylinder head 11, a housing 110' may be provided, which is secured to the cylinder head by means of bolts 111 as shown by Fig. 2. This housing at its upper side has an opening for the arm 104 and the inner portion of the barrel 109 and similarly has another opening in its lower wall for enabling adjustment of the stuffing box 30 and the avoidance of dirt collecting within the housing.

Now referring to Fig. 6, it will be observed that the upper end of the arm 104 has a rounded portion 113 which is disposed in an aperture 114 formed in a reciprocating member 115 in the barrel 109. At either end of the opening 114, a bearing element 116 is provided which is secured in place by means of screws 117 threaded into the member 115, and these elements form bearing seats for the rounded portion 113 of the arm 104. It will be observed that the bottom side of the aperture 114 has diverging side walls as indicated at 118 to permit rocking movement of the arm with respect to the member 115 without interference. Adjacent the aperture 114, the outer surface of the member 115 is threaded to receive a sleeve 120, and this sleeve is adjustably locked in position by means of a lock nut 121. The outer end of the sleeve 120, as best shown by Fig. 2, has an opening defined by three circumferentially spaced cylindrical surface sockets 122, 123 and 124 whose axes converge toward the outer end of the sleeve.

Fig. 10 also shows the sockets 122, 123 and 124 but on a section farther from the right end of the sleeve. It will be observed from Figs. 8 and 10, that each of such sockets beginning from the right end of the sleeve is less than semi-cylindrical, and that the arc of the surface becomes larger gradually until at the section shown by Fig. 10 the socket is substantially greater than semi-cylindrical.

Each of such sockets receives a jaw 125 having its outer surface cylindrical to fit the socket in which it is disposed, and the inner surface of this jaw as best shown by Fig. 6, while curved, has its axes of curvature substantially parallel to the axis of the sleeve. In other words, each jaw has an inner, substantially cylindrical surface gripping portion having an axis of curvature substantially parallel to the length of the sleeve and an outer cylindrical surface portion, the axis of curvature of which is directed at an angle to the axis of the sleeve. The outer cylindrical surface of the jaw also increases in arc size as shown by Figs. 8 and 10, so that each jaw within the ordinary relative movement of jaw and socket that will occur, will be dove-tailed in the sleeve by the encasing of its greater than semi-cylindrical portion by the greater than semi-cylindrical portions of the socket. It will therefore be apparent that when any and all jaws are moved in their respective sockets, their outer surfaces will remain in contact with the cylindrical surface in the sockets while the gripping portions thereof will be maintained substantially in parallelism although naturally they will contract or expand with respect to the axes of the sleeve. It might be added in

this connection that preferably the gripping surface of each jaw is provided with grooves or threads as indicated at 126, and such threads or grooves may be like that shown in Fig. 13, in which one side is radial, the base substantially axial, and the other side axially tapered inwardly toward the axis, in a direction away from the outer end of the jaws. For holding the jaws toward the outer end of the sleeve, a three legged stool-like element indicated at 127 is provided, which is reciprocatory in the sleeve, and which has legs 127' projecting into the respective sockets in the end of the sleeve, and into contact with the respective jaws. The stool-like element is urged against the jaws, by a spring 128 engaging the end 15 of the element, and encircling a reduced cylindrical portion 129 on the end of the member 115, and abutting a shoulder thereon.

The outer end of the barrel 109 is provided with an anvil plate 131 which is held in position by 20 swaging or spinning over a marginal flange on the end of the barrel indicated at 132. The rivet to be set generally may comprise a tubular female member indicated at 135 in Fig. 10 having a head 136 for engaging the outer side of a structure 137 being riveted. The inner end of the female member is engaged by a head 138 on a male shank 139 projecting through the female member and beyond the head 136 to provide a gripping portion 140. This latter portion preferably has grooves 30 or threads 140' for coaction with the grooves or threads 126 on the jaws, which have radial sides for engaging the radial sides of the latter threads. The tapered parts of the threads on the jaws of course facilitate entry of the male rivet member 35 between them. In order to facilitate initial entry of the male member between the jaws, the end of such member may be beveled or the jaws may be countersunk. The anvil plate 131 has an opening 141 for receiving the projecting end of the 40 male member, and such projecting end is adapted to be positioned between the jaws and to be gripped thereby when the rivet is set. The anvil also has a conical recess 142 for engaging the head 136 on the female rivet member. In setting the 45 rivet, it may be inserted as shown by Fig. 6, and then the machine and rivet may be moved into such positions that the rivet projects through the openings in the structure 137 as shown by Fig. 10. Then by so operating the machine, that the member 115 is moved to the left in the barrel 109, the 50 jaws will grip the male member and pull it, and the reactionary force to the pull naturally will be imparted through the anvil 131 against the head 136 on the rivet. It follows that the male member 55 will be moved through the female member, and that the head 138 compressing the female member inwardly of the structure, will cause a head to be bulbed against the inner side of the structure. Preferably the inner face of the anvil 131 has a 60 central boss 145 which may serve as a stop for the jaws, when the sleeve 120 is in its right end position in the barrel 109, if the jaws have not already contacted with each other. Ordinarily the jaws are in such contracted condition, however, that 65 whether they engage each other or the boss 131, they will be separated and hence moved back accordingly in their sockets upon inserting the male rivet member between them. This insertion is of course facilitated by the beveled end of the rivet 70 member or by counter-sinking the opening between the jaws. The separation of the jaws upon inserting the male rivet member insures gripping thereof, by action of the spring 128, and ordinarily it will be very difficult to retract the rivet mem- 75

ber after it is once inserted, particularly where threads or grooves are provided on the jaws and member.

When a rivet is set, it is only necessary to pull the trigger 93, which will cause the piston to move to the right in the cylinder, and this in turn will cause the arm 104 to pivot about its pivot 105 and the arm to move the reciprocating member 115 and the sleeve 120 attached thereto, to the left in the barrel 109. When the rivet is inserted between the jaws, they may be moved apart slightly, and after the rivet is inserted, the spring 128 will cause the jaws to have a gripping action on the rivet. Then upon movement of the member 115 and sleeve 120 to the left, it is apparent that the cylindrical surfaces in the inner end of the sleeve 120, will cause the jaws to move inwardly to contract about and grip the male rivet member positively, the spring 128 facilitating obtaining this grip. Owing to the fact that the gripping surfaces of the jaws will be substantially parallel to the male member throughout any gripping movement of the jaws, full length contact of the jaws with the male member and hence a more positive grip thereof, may be obtained. Upon continued movement of the member 115, it is apparent that the rivet will be set in the manner previously described. After the bulb head is formed at the inner side of the structure 30 to be riveted, continued movement of the member 115, and hence pulling of the male member will break it substantially at the groove or neck 150, (Fig. 10) which at this time preferably will be disposed substantially at the outer surface of the head 136 on the female member. When such break occurs, the recoil of the jaws and stool will effectively be cushioned by the spring 128, and the slowly exhausting fluid in the right end of the cylinder will cushion the other moving parts of the machine. When the male member is thus broken the recoil of the jaws may open them and cause the broken part to be thrown back or the broken part may remain between the jaws until such time that another rivet is inserted. In either case the broken part of the male member will be moved backwardly through the stool 127, which has a central aperture to permit such movement, and then through a recess 151 in the member 115 and then through openings 152 and 153 in the bottom side of the sleeve 120 and the lower wall of the barrel 109. The recoil of the jaws also will overcome any tendency of the jaws to stick in their sockets.

The provision of the small barrel 109, and having it offset with respect to the piston rod and machine, naturally facilitates riveting in corners and other more-or-less inaccessible places, and having the barrel cylindrical also facilitates riveting in inaccessible places, and probably provides a most efficient shape to obtain the maximum universal use. For the purpose of enabling riveting in very narrow and perhaps deep openings, a tapering attachment anvil 160 as shown by Fig. 11, 60 may be provided which has a cup portion 161 adapted to abut the anvil 131 on the barrel, and an internally threaded cylindrical wall 162 adapted to be threaded around the end of the barrel. This attachment anvil at its outer end is about 70 the size of the female rivet head and has a recess 163 for engagement with the head and an aperture longitudinally thereof indicated at 164 for receiving the male member. In a case of this type, the male rivet member naturally would have 75 to be longer so that it could be inserted through

the attachment anvil into a position for engagement with the jaws, and it may be necessary to elongate openings in the sleeve 120 and member 115 to allow the broken rivet element to be ejected after setting the rivet.

The rivet setting machine described and illustrated, is extremely compact, preferably composed of very light material, such as aluminum or aluminum alloys and is so constructed that its use is practically universal. It is apparent that a highly efficient arrangement has been provided to obtain a great rivet setting force without necessitating the use of a large piston, or undesirably large fluid pressures. It is apparent also that an arrangement has been provided by means of which the male rivet member will be gripped positively and uniformly in all cases and that this will occur even though the male member varies in size within a considerable range. The adjustable mounting of the sleeve 120 on the member 115 permits adjustment of the sleeve with respect to the anvil 131, and is desirable to obtain maximum efficiency and to accommodate various dimensions of rivets.

Although only one form of the invention has been described and illustrated in detail, it will be apparent to those skilled in the art that various modifications may be made without departing from the scope of the appended claims.

We claim:

1. A mechanism for applying to a structure a rivet including a female member and a male member extending through the female member for forming a head on the latter on one side of the structure, which comprises a member adapted to engage the end of the female member around the male member, jaws for gripping, pulling and finally breaking the male member after formation of said head, means movable axially of the jaws and substantially aligned therewith for causing the latter to grip and then pull the male member, and means for allowing the broken male member to pass through the jaw means, movable means and first member, by its continued movement in the direction in which it was pulled.

2. A mechanism for applying to a structure, a rivet including a female member and a male member extending through the female member for forming a head on the latter at one side of the structure, which comprises a frame, means movable in the frame for gripping, pulling and breaking the male member, and an anvil on the frame for applying the reactionary force of the pull against the female member, and having an aperture for receiving the male member, said movable means and frame member having cooperating openings for allowing the broken part of the male member to pass therethrough in the direction in which it was pulled, upon completion of the riveting operation.

3. A mechanism for applying to a structure, a rivet comprising a female member, and a male member extending through the female member for forming a head on the latter at one side of the structure, comprising a frame, an anvil on the frame for abutting the female member and having an opening for receiving the male member, a movable member in the frame, having an opening in its end adjacent the anvil defined by surfaces converging toward the anvil, and a plurality of jaws between such surfaces having outer surfaces contacting therewith, the surfaces on the jaws and movable member being of such character that they conform to one another regardless

of movement of the jaws longitudinally of the member.

4. A mechanism for applying to a structure, a rivet including a female member and a male member extending through the female member for forming a head on the latter at one side of the structure, which comprises a frame, an anvil on the frame for abutting the female member, and having an aperture for receiving the male member, a movable member in the frame and having an opening in its end adjacent the anvil defined by cylindrical surfaces whose axes converge toward the anvil, and a plurality of jaws having cylindrical surfaces, each of which contacts with a cylindrical surface on the movable member, the surface on each jaw and on the movable member cooperating therewith, being of such character that the jaws are positively retained in contact with the surfaces on the movable member but are free to move along such surfaces in converging paths.

5. A mechanism for applying to a structure, a rivet comprising a female member, and a male member extending therethrough for forming a head on the latter at one side of the structure, comprising a frame, an anvil on the frame for abutting the female member, a movable element in the frame having converging surfaces, and separate jaws between said surfaces interlocked with the element to move parallel to such surfaces, said jaws having threads and grooves for interlocking with threads and grooves on the male rivet member.

6. A mechanism for applying to a structure, a rivet comprising a female member, and a male member extending therethrough for forming a head on the latter at one side of the structure, comprising a frame, an anvil on the frame for abutting the female member, a movable element in the frame having converging surfaces, and separate jaws between said surfaces interlocked with the element to move parallel to such surfaces, said jaws having threads and grooves for interlocking with threads and grooves on the male rivet member, said threads on the jaws being inclined to facilitate insertion of the male rivet member therebetween.

7. A rivet setting machine comprising an outer member, an intermediate member reciprocatory in the outer member, and having an opening in one end defined by converging surfaces, each of which in any cross section perpendicular to its length has a surface contour conforming to any other similar section taken along the length of the intermediate member, and jaws between said surfaces having outer surfaces substantially complementary to the surfaces on the intermediate member, so that in movement of the jaws along the intermediate member, they may remain in full surface contact with said surfaces on the intermediate member.

8. A rivet setting machine comprising an outer member, an intermediate member reciprocatory in the outer member, and having an opening in one end defined by cylindrical surfaces whose axes converge toward one end of the member, and jaws having cylindrical outer surfaces complementary to the surfaces on the member, and inner gripping surfaces.

70 9. A rivet setting machine comprising a barrel, an outer member, an anvil plate at one end of the member, and having an opening for a rivet shank and a recess for the head on a tubular rivet member through which the shank projects, a reciprocatory member within the outer member and hav-

ing spaced surfaces converging toward the opening in the anvil, in which each surface in any lateral cross section throughout its length is of conforming contour to any other lateral section, and jaws between said surfaces and having outer surfaces complementary to the surfaces of said intermediate member, and inner gripping surfaces for the rivet shank.

10. A machine for setting a rivet comprising a female member and a male member extending therethrough, for forming a head at one side of a structure to be riveted, and which is adapted to be broken intermediate its ends while under tension, after setting of the rivet, wherein the machine comprises a barrel having an apertured anvil at one end for engaging the end of the female member while allowing the male member to project therethrough, contractile jaws in the barrel for gripping the male member, a movable member in the barrel for contracting the jaws and then pulling the male member to set the rivet, means for moving said movable member to set the rivet and to finally break the male member, and means for allowing the broken end of the male member to move through the jaws and barrel and to be ejected from the latter in back of the jaws.

11. In combination, means for gripping and pulling a rivet member away from a structure, means for applying the reactionary force to the structure, and means for cushioning movement of the gripping and pulling means upon separation of the member with respect to the structure.

12. A mechanism for applying to a structure, a rivet including a female member and a male member extending through the female member for forming a head on the latter at one side of the structure which comprises means for gripping and pulling the male member, means for applying the reactionary force to the female member, and means for cushioning movement of the first means upon separation of the male member with respect to the structure.

13. A machine for setting a rivet comprising a female member and a male member extending therethrough for forming a head on one side of a structure to be riveted, and which is adapted to be broken intermediate its ends while under tension after setting of the rivet, which comprises an outer member having an apertured anvil at one end for engaging the end of the female member while allowing the end of the male member to project through the aperture, an intermediate and movable member having inner converging surfaces adjacent the anvil on the first member, jaws in the intermediate member for engaging the end of the male member projecting through such aperture in the anvil, said jaws having outer surfaces angularly arranged with respect to the axis of the movable member and engaging the converging surfaces of the movable member, means for moving the latter member for first causing gripping of the male member by the jaws and then longitudinal movement of the latter to move the male member, and means for allowing the broken part of the male member engaged by the jaws to pass rearwardly therethrough and through the other members and to be ejected therefrom upon setting of the rivet and breaking of the male member.

14. A machine for setting a rivet comprising a female member and a male member extending therethrough for forming a head on one side of a structure to be riveted, and which is adapted to be broken intermediate its ends while under tension after setting of the rivet, comprising an

- outer member having an apertured anvil at one end for engaging the end of the female member while allowing the end of the male member to project through the aperture, an intermediate 5 and movable member having inner converging surfaces adjacent the anvil on the first member, jaws in the intermediate member for engaging the end of the male member and having outer surfaces angularly arranged with respect to the 10 axis of the movable member and engaging the converging surfaces of the movable member, means for moving the latter member for first causing gripping of the male member by the jaws and then causing a longitudinal movement of the 15 latter to move the male member, and means depending on the recoil force on the jaws for freeing them from the broken male member after setting of the rivet and upon breaking of the male member under tension.
- 20 15. A machine for setting a rivet comprising a female and male member extending therethrough for forming a head on one side of a structure to be riveted, and which is adapted to be broken intermediate its ends while under tension after the setting of the rivet, comprising an outer member having an apertured anvil at one end for engaging the end of the female member while allowing the end of the male member to project therethrough, an intermediate and movable member having inner converging surfaces adjacent the anvil on the first member, jaws in the intermediate member for engaging the end of the male member having outer surfaces angularly arranged with respect to the axis of the 25 movable member and for engaging the converging surfaces of the movable member, means for moving the latter member for first causing gripping of the male member by the jaws and then a longitudinal movement of the latter to move 30 the male member, means for allowing the broken part of the male member engaged by the jaws to pass rearwardly through the latter and to be ejected therefrom upon setting of the rivet and breaking of the male member, and means depending upon the recoil force on the jaws for 35 freeing them from the broken male member after setting of the rivet and upon breaking of the male member under tension.
16. In a rivet setting machine, a barrel having 40 an anvil at one end for engaging one part of a two-part rivet, jaws in the barrel for engaging the second part of the rivet, an intermediate movable member in the barrel for causing contraction of the jaws and movement of the last 45 mentioned part of the rivet and breaking thereof from the rivet connection after setting of the rivet, and means for allowing the broken part of the rivet member to pass rearwardly through the jaws and to be ejected from the barrel.
- 50 17. In a machine for setting a rivet wherein a rivet pin is pulled and a portion of the pin finally separated from the structure riveted, which comprises means for gripping and pulling the pin, means for applying the reactionary force of the 55 pull to the structure riveted, and means for allowing the separated pin portion to move rearwardly through the gripping means and a part of the machine.
- 55 18. In a machine for setting a rivet wherein a rivet pin is pulled and a portion of the pin finally separated from the structure riveted, which comprises means for gripping and pulling the pin, means for applying the reactionary force of the 60 pull to the structure riveted, and means for cushioning the gripping means upon separation of the pin portion.
19. In a machine for setting a rivet wherein a rivet pin is pulled and a portion of the pin finally separated from the structure riveted, which comprises means for gripping and pulling the pin, means for applying the reactionary force of the pull to the structure riveted, means for allowing the separated pin portion to move rearwardly 65 through the gripping means and a part of the machine, and means for cushioning the gripping means upon breaking the pin.
20. In a machine for setting a rivet wherein a rivet pin is pulled and a portion of the pin finally separated from the structure riveted, which comprises fluid operated means for gripping and pulling the pin, means for applying the reactionary force of the pull to the structure, and means for resiliently resisting movement of the fluid operated means.
21. In a machine for setting a rivet wherein a rivet pin is pulled and a portion of the pin finally separated from the structure riveted, which comprises fluid operated means for gripping and pulling the pin, means for applying the reactionary force of the pull to the structure, and fluid pressure means for resiliently resisting movement of the fluid operated means.
22. A rivet setting mechanism for setting a rivet wherein a rivet pin is pulled and a portion of the pin is broken from the structure riveted, which comprises jaws for gripping the pin, a movable member for moving the jaws to pull the pin, and means for cushioning movement of the jaws upon breaking of the pin with respect to the 30 structure.
23. A rivet setting machine or the like, comprising an outer member, an inner tubular member reciprocator in the outer member and having inner tapered surfaces at one end, jaws between and operatively engaging said surfaces, and means normally urging the jaws toward the smaller end of the tapered surfaces, said means including means for applying a separate force to each jaw.
24. A rivet setting machine or the like, comprising an outer member, an inner tubular member reciprocator in the outer member and having inner tapered surfaces at one end, jaws between and operatively engaging said surfaces, and means normally urging the jaws toward the smaller end of the tapered surfaces, said means including a member having legs for engaging the ends of the jaws respectively.
25. A rivet setting machine or the like, comprising an outer member, an inner tubular member reciprocator in the outer member and having inner tapered grooves at one end, jaws disposed in said grooves respectively, and means normally urging the jaws toward the smaller end of the 40 tapered grooves, said means including elements projecting axially into the grooves and engaging the jaws respectively.
26. A rivet setting machine or the like, comprising an outer member, an inner tubular member having inner tapered surfaces at one end, a reciprocator member at the opposite end of the inner member and projecting thereinto, jaws in the inner member and operatively engaging said surfaces, and means normally urging said jaws 50 toward the smaller end of the tapered surfaces and including means engaging the inwardly projecting portion of the reciprocator member.
27. A rivet setting machine or the like, comprising an outer member, an inner tubular mem- 55

ber having inner tapered surfaces at one end, a reciprocatory member at the opposite end of the inner member and projecting thereinto, jaws in the inner member and operatively engaging said surfaces, and means normally urging said jaws toward the smaller end of the tapered surfaces

and including a spring encircling a part of the inwardly projecting portion of the reciprocatory member.
